UNITED STATES PATENT OFFICE

HAROLD N. RICE, OF ATTLEBORO, MASSACHUSETTS, AND HAROLD V. WALSH, OF CITY
ISLAND, NEW YORK

DESIGN FOR A STATUETTE OR ANALOGOUS ARTICLE

Application filed June 20, 1932. Serial No. 44,152. Term of patent 3½ years.

To all whom it may concern:

Be it known that we, HAROLD N. RICE and HAROLD V. WALSH, citizens of the United States, residing, respectively, at Attleboro, county of Bristol, and State of Massachusetts, and at City Island, county of New York, and State of New York, have invented a new, original, and ornamental Design for a Statuette or Analogous Article, of which the following is a specification, reference being had to the accompanying drawings, forming a part thereof.

In the drawings,

Figs. 2 and 3 are perspective views showing chiefly the opposite sides, respectively, of the statuette; and

Fig. 4 is a rear view of the statuette.

While the invention is herein illustrated as embodied in a statuette, it is contemplated that it may also be used in an analogous article such, for example, as a door stop, paper weight, book end, or the like.

We claim:

The ornamental design for a statuette or analogous article, substantially as shown and described.

HAROLD N. RICE.
HAROLD V. WALSH.
